4 Claims. (C.I. 223—76)

This invention is concerned with dyeboarding systems for the finishing of textile garments, i.e. systems in which manufactured garments are shaped on forms and are also dyed, whilst on these forms. Ladies' stockings are a very typical example of garments which can be finished in this way and, for convenience, the following description will be confined to this particular application, it being understood that the invention also covers analogous applications.

In the present invention we present a method of finishing textile garments in which these garments, mounted on forms, are successively subjected to separate treatment steps comprising (a) exposure of the goods to steam at superatmospheric pressure in a closed chamber, (b) showering of the goods with dye or similar treating liquor at atmospheric, or substantially atmospheric pressure to dye them, and (c) exposure of the goods to hot air for drying the same, the forms being stationary and maintained in situ in a single treating zone throughout these treatment steps.

Such a possibility affords a number of advantages, some of which will later be mentioned. Not least of these advantages is the fact that this arrangement avoids the shifting of the goods from one zone to another between finishing steps and thus avoids the delay and temperature losses which this inevitably involves, and possible contamination of the goods.

In performance of this invention the various steps can be carried out in automatic sequence and each for a pre-set period. This affords a rational and at all times uniform treatment, which can be adjusted as found judicious.

It is, moreover, an advantage to shower the goods with dye liquor, inasmuch as the liquor can then be used in economical doses. Further, each such dose of liquor being recirculated and re-used in dyeing a particular batch of goods and then discharged, each batch of goods is treated with fresh, clean liquor.

A plant, also prescribed by this invention, for implementing these methods comprises a treating chamber which can be closed to enclose form-mounted garments in a treating zone, a showering means located above said treating zone, a liquor feed pump connected at one side to said showering means and at the other side to a liquor drain from the chamber, and hot air blowing and evacuating means located outside said chamber.

A device, e.g. a series of cams on a common camshaft, can be used to control the automatic and sequential operation of valves and other units governing the admission or supply of various treatment media to the treatment zone.

The closed chamber may be formed by a vessel, conveniently cylindrical, having an upper section or bell which can be raised and lowered relatively to a fixed base, respectively to admit and confine the stocking forms. In this event the raising and lowering of the bell can be performed pneumatically under the control of the cam device, as can also means for locking the bell in its "down" position before and during the finishing treatments.

The plant will advantageously also include a pump for recirculating dyeing liquor through the shower device and the vessel during a dyeing step, thereby to make maximum

2

effective use of each dose of dyeing liquor, as referred to above. This pump can be arranged to receive each dose from a more voluminous static reservoir, and the infeed and draining of each successive dose, and the starting and stopping of the pump, can be controlled by valve means in the main air system of the plant and controlled from the aforesaid camshaft.

Again, the plant may include means to heat each dose of dyeing liquor during its recirculation and when actually dyeing, i.e. to maintain this dose (which may in any event be preheated in the reservoir) accurately at the requisite dyeing temperature at the critical time. This heating means, or make-up heating means, may involve the use of a heat exchanger which is charged with available steam at appropriate times, once again by the timed opening of valve means in the main air system.

The steam for boarding purposes can be admitted through nozzles or apertures in the chamber (e.g. in the fixed bottom section of the latter), and once again can be cut in or out by valves controlled by the camshaft referred to. The steam admission to these nozzles or apertures can be branched to the dye liquor pre-heating means in the reservoir and the make-up heater (e.g. exchanger).

Furthermore the steam valves governing the admission of boarding steam to the closed chamber may be automatically regulable, to maintain pre-set treatment temperatures, by thermostatic means in this chamber. Similar thermostatic means can be used to regulate the temperature at the heat exchanger, thereby to maintain the dyeing liquor at correct temperature at the point of use.

Each dose of dyeing liquor is conveniently gravity fed from a dye liquor reservoir which is self-filling with fresh dye liquor at a pre-set, but adjustable, concentration. This reservoir, in fact, has associated therewith a dye bowl, each with a self-centering mechanism, which is arranged to discharge a specific quantity of dye, or dye and additives or equivalent, into the reservoir simultaneously with the withdrawal of mixed liquor therefrom by the pump. At the same time water is added to the reservoir, and the simultaneous operation of the dye concentrate, and water feeds, and the delivery of the dose of mixed liquor can be implemented by a single valve which, again, is incorporated on the main air system.

By a further feature of the invention, the apparatus also includes an advantageous form of fixed drying equipment which is arranged to project hot air in a positive cycle through the dyed goods still standing in the treatment zone, but with the bell of the vessel raised.

A form of dyeboarding system within the present invention will now be described with reference to the accompanying diagrammatic drawings.

In this system the treating zone is generally designated A, and shown at this zone is the aforementioned chamber which is defined by a retort with an upper section 1 in the form of a vertically-movable cylindrical bell with a domed top, and a fixed, shallow-dished, part-spherical base 2.

The cylindrical bell 1 is capable of being raised and lowered by means of a pair of jacks of known form attached to opposite sides thereof, a part of one of these jacks being diagrammatically indicated at 3. The rams of the jacks are raised by compressed air supplied through a line 68 connected in a main air system with which the plant is provided (see below), and the air supply to operate the jacks is controlled by a cam-operated reversible valve 69.

When the bell 1 is in its bottom position its lower edge is firmly seated, through packing means, on a rim on the base 2 to close the chamber. In this closed condition, i.e. that shown in the drawing, the bell is secured to the base by locking means (not shown but also of known

form) which are actuated by a pneumatic piston-cylinder unit 4 operable by air impulses through a line 5 also connected in the main air system with which the plant is equipped. In this case the supply of operating air to the respective sides of the cylinder of unit 4 is under the control of a cam-operated reversing valve 70.

The base section 2 also serves to support a pair of parallel horizontal rails 6 forming a section of track within the closed container and intended for support of a stocking-form carriage. Aligned with this track section 6, outside the chamber 1, 2 and extending from opposite sides of the latter, are two similar track sections (not shown), and the principle is that a carriage, such as 7, carrying upstanding stocking forms 8, can run from one of the external trackway sections at required times on to the central sections 6, whilst a second such carriage is expelled from the latter to run out on to the other external trackway section.

This arrangement allows for alternation of two carriages at the treatment zone, so that the forms on one carriage can be stripped and reloaded with fresh stockings, whilst the stockings on the other forms are undergoing treatment. Further details of the carriages, the forms thereon and the carriage operating mechanism will not here be further described, since they can take the form described in our British Patent No. 810,605, or be such as to perform a similar function.

Also mounted on the fixed base 2 is an annular tube 9 which is perforated with a series of orifices or nozzles and is connected through a conduit 10 to a steam source. Included in this conduit 10 is a diaphragm valve (steam-valve) 11 which is normally closed but is operable by air impulses from a line 72 in the aforementioned main air system, controlled by a cam-operated valve 71 (see below). The conduit 10 also includes a manually-operable shut-off valve 12, and a reducing valve 13 which can be adjusted to suit the pressure of the incoming steam to the required figure.

A secondary control of valve 11 is exercised by a temperature-responsive instrument 56 governed by a thermostat 57 mounted in the base 2 of the retort, and arranged to operate valve 71 and thereby initiate closure of the valve 11 through a branch line 73 also connected in the main air system, when a specific temperature, which can be preset in the instrument 56, prevails in the chamber 1, 2.

The dome of the bell 1 is equipped with air vents 14, which may also be operable by air from the main air system, and a spring loaded pressure relief valve 15 to place an upper limit on the pressure developed at any time within the closed chamber. The base 2 is provided with drain and steam exhaust means which, in this instance, is assumed to be a single opening at the centre of base 2. This is coupled to a conduit 16 leading to a drain.

A further fixture at the treatment zone A is a pipe 17 which upstands from the base 1 and is angled at its upper end and there carries a shower head 18 representing a dye liquor distributor. Conveniently this shower head will comprise a hollow casing with a plurality of sprinkler orifices distributed over the lower surface thereof in a pattern suited to the arrangement of forms closed up in packs on a carriage 7 standing in the retort.

Mounted in a convenient position in the vicinity of the treatment zone A is a dye liquor reservoir in the form of a closed tank 19, this being arranged for the dosing of dye liquor to the shower 17/18 at appropriate times. To this end it has, at a lower part, a filter covered outlet 20, connecting to a gravity conduit 21 in which is disposed a diaphragm valve (dye liquor valve) 22 controlled by air impulses from the main air circuit. Conduit 21 is connected through a four-way union 23 to the suction side of a dye liquor pump 24, the delivery side of which is connected through a conduit 25 with the shower stand-pipe 17. The union 23 is also coupled to the exhaust

conduit 16, and a further diaphragm valve (exhaust valve) 26 operable by air from the main supply through a line 75 under the control of a cam-operated valve 74, is incorporated in conduit 16 at the drain side of union 23.

From the foregoing it will be apparent that having admitted liquor through valve 22 to the suction side of the pump, it is possible by closing this valve, and valve 26, to effect a re-circulation of the admitted dose of liquor through a closed circuit consisting of the union 23, the suction side of pump 24, conduit 25, the standpipe 17, the shower head 18, over the stockings disposed in the chamber, through conduit 16, back to the suction side of the pump, and so on.

For the purpose of maintaining the temperature of dye liquor circulated in this way, it will be noted that a heat exchanger 27 is arranged in the conduit 25, this consisting of a canister in which a serpentine portion of the conduit 25 is housed and which is connected through a branch conduit 28 with the steam inlet conduit 10, and through a discharge conduit 29 with the drain conduit 16. Another diaphragm valve (exchanger valve) 30 connected to the main air system through a line 76, is interpolated in conduit at the steam inflow side of the heat exchanger 27, whilst the discharge from the latter includes a non-return valve 31 and a steam trap 32.

As will readily be observed, when valve 30 is opened, steam from the admission conduit 10 will flow into the canister of the heat exchanger 27 and will eventually be discharged through the trap 32, in so doing maintaining the temperature of the dye liquor being circulated by the pump 24 in the closed circuit referred to above. To allow for a sensitive control of the dye temperature, a thermostat is disposed in the path of the dye liquor in the heat exchanger and is connected through an electrical lead 33 to a control instrument 34 of known type which can be present by means of a pointer thereon, to respond at a chosen temperature to open a valve in the instrument and cause air to be passed from the main air system to valve 30 to operate the latter and shut down valve 30 until required temperature conditions are restored. The dye liquor will, in fact, be supplied in preheated condition from the tank 19 (see later) and the function of the heat exchanger 27 will be to ensure and maintain the required temperature of each dose of liquor during the period it is being closed-circuited.

The preheating of the dye liquor is performed by a steam heating coil 35 which is disposed at this lower part of tank 19 and is supplied from the main steam admission conduit 10 through a branch 36 incorporating another diaphragm valve 37 connected to the main air system through a line 77, and the discharge from the coil 35 is through a conduit 38 to the drain 16. Here again the steam discharge contains a non-return valve 39 and a steam trap 40.

Further, in the interests of economical operation of the system, steps are taken to exert a fairly close control on the temperature of the liquor in the tank 19, and for this purpose a thermostat in the latter is connected through a line 41 to a pre-settable, temperature-responsive instrument 42, similar to 34 and 56, for controlling the air impulses which will respectively open and close the steam admission valve 37.

To allow for control of the proportions of the dye mixture in the tank 19, arrangements are made for the metering of the various components used. For this purpose the tank 19 is surmounted by one or more dye bowls 43 arranged to contain dye concentrate (or other required components) for the dyeing or treating mixture, and this bowl, or each of these bowls, is arranged to feed through a gravity conduit 44 into the top of the tank 19. The dye bowl or bowls can be used for making up the required dyeing colour and may in addition, or alternatively, be used to introduce other additives to the intended mixture.

The or each dye bowl 43 is filled through its open top where it is provided with a filter 45, and it contains a

stirrer 46 operable by an electric motor. The conduit 44 has a metering device 47 branched therefrom, this device consisting of a graduated tubular vessel having therein a piston which can be set to a measured position along the tube by a manually-operable screw means 48.

A diaphragm valve (metering valve) 49 at the junction of this device with the conduit 44 is operable by an air impulse from the main air system to connect the metering vessel 47 alternatively to the dye container 43 or to the tank 19, thus allowing the charging of a specific and measured small quantity of dye concentrate or like component into the latter as demanded. As will later be apparent, a make-up quantity of dye concentrate can automatically be dispensed into the tank 19 when a dose of liquor is discharged therefrom to the dyeing zone.

Simultaneously with the admission of dye concentrate or the like from the bowl or bowls 43, water is admitted to tank 19, and this through a conduit 50 in the appropriate quantity and under the dictation of yet another diaphragm valve 51. The operation of the dye-concentrate valve 49 and the water-admission valve 51 can be interlocked by control means so that the one is operated simultaneously with the other. In fact, in the system illustrated not only are the admissions of the dye concentrate and water to tank 19 interlinked with one another, but also with the discharge of doses of mixed dyeing liquor from the reservoir tank 19.

Thus it will be seen that the air lines 78, 79 and 80, respectively directing air impulses to the dye liquor dosing valve 22, the metering valve 49, and the water valve 51, are themselves branched from a line 82 of the main air system through a common cam-operated valve 81.

It will also be noted that a float 52 is provided in tank 19 as a safety device to exert an overriding control and limit the further admission of water and concentrate when the contents of the tank are at a predetermined top level. The level can be checked at any time through an external gauge 55. A stirrer 53 is also provided for ensuring a homogeneous mixing of the contents of the tank, this being operated by an electric motor 54.

Finally we refer to the means which are used for drying the treated goods in the system. For this purpose a fixed hot air blower nozzle 58 is associated with, but unconnected to, the bell 1 and is located outside the latter so as to extend alongside the lower parts of the carriage-mounted forms standing in the zone A. This directs hot air primarily towards the welts of the stockings—which require most intensive drying. At the opposite side of the zone, and in register with the nozzle 58 is a fixed suction nozzle 59, and these two nozzles are interconnected through a hot air unit which is diagrammatically indicated and generally denoted 60. In the drawing this unit appears to surmount the retort 1, 2, but this is purely a result of the diagrammatic showing and, in practice, the unit will be located adjacent the lower part of the retort and at one side thereof.

It comprises a pair of fans 61 and 62 which are operable in common and arranged so that the delivery side of fan 61 is connected to the suction side of the fan 62 through a communicating conduit 64, which is provided with a fresh-air inlet 63. Associated with fan 62 is an air heater 81 which conveniently comprises a steam heating coil connected through a conduit 65 to the same steam source as conduit 10. A steam trap 66 is provided at the return side from the heater in fan 62. Conveniently the fans 61 and 62 are electrically driven and are started in response to the closure of a switch 67 when the bell 1 is raised. The major part of the hot air will be withdrawn through the nozzle 59 and re-circulated so that a large part of its sensible heat is retained. Not only is this re-circulation economical, but it also safeguards any nearby operative from exposure to any substantial quantity of hot air.

Throughout the foregoing reference has been made to the control of the various initiating and arresting or change-

over means of the system from a main air circuit. This is conveniently implemented by a set of cams on a common camshaft which are arranged so that they become effective, in timed sequence, as the result of a slow continuous rotation of the camshaft, to open valves for the intended purpose. These valves can be of a simple mechanical on-off type and have been referred to above as "cam-operated" valves. Where electrical operations are required, further cams on the camshaft can be arranged to operate electrical switches for this purpose. Details of this camshaft, and the means operated thereby have not been specifically illustrated, since they are common in this art and can readily be devised by any skilled person. Their function will be made even clearer by the particular example, now to be given, of the operation of a dyeing and drying process, in accordance with this invention, in the system described above.

As a prelude, it is pointed out that the basic sequence of steps in this procedure is the conveyance of a set of freshly-knitted stockings, mounted on forms on a carriage, into the treating zone A, the closure of the retort or chamber 1, 2 about the forms arrested in this zone, the introduction of steam to preboard the stockings at elevated temperature, the opening of the exhaust from the chamber to vent the steam therefrom, the showering of the stockings with a single batch of dye liquor which is recirculated over the stockings for a predetermined period and then discharged, the admission of further steam for a short period to flush the drain and, in so doing, to some extent postboard the dyed goods, the opening of the retort, the blowing of hot drying air against the goods, still standing in the treatment zone A, and the removal of the carriage from this zone.

Starting then from the juncture at which the bell 1 is raised, a carriage with dyed stockings stands beneath it with air blowing across it from 58, and a fresh carriage is standing ready outside the treating zone with untreated stockings on its forms. The operative presses the start button of the conveyance system (see British Patent No. 810,605) so that this carriage moves along its trackway into the treating zone and, in so doing, expels from the latter the old carriage with already-treated stockings.

On arrival in its end position, the fresh carriage closes a switch to start the rotation of the camshaft referred to above. The first-effective cam on this shaft operates valve 69 so that the compressed air supply to jacks 3, which has been effective to hold the bell 1 in its upper position, is cut off, and the bell is allowed to descend at a slow rate by a slow bleed of air from the undersides of the jack pistons. During this descent the switch 67 is operated to stop fans 61 and 62.

When the retort has reached its bottom position a second cam actuates valve 70 so as to bring the bell locking means into operation to firmly fasten the bell 1 to base 2. A safety switch (not shown) on the base can shut off the camshaft motor if the bell is not properly "down" at this stage.

A third cam now actuates valve 74 to close valve 26 and the drain from the chamber 1, 2, and a fourth cam operates valve 71 so that steam flows through tube 9 upwardly into the closed chamber. This steam is controlled at a temperature of about 255° F. by the thermostatic instrument 56, and the consequent preboarding treatment of the stockings is pursued for about 30 seconds.

At the end of this phase, valve 71 is cam-operated to cause closure of steam valve 11 and simultaneously valve 74 is actuated to open drain/exhaust valve 26, whilst a further cam opens the vents 14.

After a pause, the next-operative cam on the camshaft re-actuates valve 74 to close 26 and, practically simultaneously valve 81 is operated by a cam to trigger off the dosing valve 22. As a result a dose of already-mixed dye flows through 20 to the closed dyeing circuit described above, in an amount controlled by the operation of valve 81 by yet another cam so that valve 22 is closed

and simultaneously metering valve 49 and water valve 51 are opened to admit appropriate make-up concentrate and water to tank 19.

The pump 24 is now started by operation of a micro-switch from the camshaft and the quantity-controlled batch of dye liquor is repeatedly pumped up to the head 18, showered over the stockings and re-circulated. The period of such treatment, determined by the cam setting, can vary according to the type of work and treatment, but 2½ minutes can be given as a typical example.

Again the temperature of the dye liquor is subject to choice. However, another typical example which might be cited is a batch temperature of 200° F. (controlled at the exchanger 27 by thermostatic instrument 34), contrasting with a pre-temperature in reservoir 19 of 15 about 130° F.

After the dyeing treatment, there is a further cam operation of valve 74, and hence of valve 26 to open the drain conduit 16, and discharge the dose of dye liquor. Following this, the vents 14 are closed and steam valve 11 is re-opened and, the drain being open, it is flushed through by the steam which, in this case, is allowed by instrument 56 to rise to a temperature only of about 235° F. There may also be a partial drying and some 20 post boarding of the stockings.

The next cam-initiated steps are the closure of steam valve 11 and opening of vents 14, followed by actuation of valve 70 to unlock the bell and of valve 69 to raise it. When the rising bell trips switch 67 the fans 61 and 62 are started to blow hot air through the work, as described. 30 This returns the situation to the starting point chosen above.

We claim:

1. A method of finishing textile goods, in which these goods, mounted on a plurality of forms, are successively subjected to separate treatment steps comprising (a) pre-boarding the goods by exposure to steam at superatmospheric pressure in a single closed chamber, (b) then showering the pre-boarded goods in said chamber with heated dye liquor, said dye liquor having been heated without introducing steam thereinto, at substantially 35

atmospheric pressure to dye said goods and (c) drying the dyed goods, the forms being immobile and maintained immobile in a single treating zone throughout the successive treatment steps.

- 5 2. A method according to claim 1, in which the steam treatment of the garments is performed in a closed chamber at least before the dyeing step and this chamber is opened, without displacement of the garments, for projection of hot air against the latter in performance of the 10 drying step.
3. A method according to claim 1, in which the showering treatment is performed by recycling a controlled quantity of dyeing liquor, brought outside the treating zone to a pre-set temperature, so that it successively falls in distributed streams over the goods, is collected and is returned to re-showering, all in a continuous operation.
4. A method according to claim 1, wherein the goods are preboarded by exposure to steam at a temperature of about 255° F., then showering the goods with dye liquor heated to a temperature of about 200° F., thereafter exposing the goods in a further steam treatment step at a temperature of about 235° F., and finally drying the goods. 20
